UNITED STATES PATENT OFFICE.

OTTO E. HURST, OF STATEN ISLAND, NEW YORK.

GAME APPARATUS.

No. 882,945.

Specification of Letters Patent. Patented March 24, 1908.

Application filed December 4, 1907. Serial No. 405,079.

To all whom it may concern:

Be it known that I, OTTO E. HURST, a citizen of the United States, and a resident of Staten Island, county of Richmond, and 5 State of New York, have invented certain new and useful Improvements in Game Apparatus, of which the following is a full, clear, and exact description.

This invention relates more particularly 10 to a game of dice.

The primary object of the invention is to provide a simple and attractive game which may be played with dice or other objects having special marks or characters indicated 15 thereon; which makes the usual game of dice more interesting and capable of greater variations than the game as ordinarily played; and which minimizes the possibility of a tie in the score of the different players, resulting often in disputes and thereby destroying 20 the pleasure derived from a game of this kind.

A further object of the invention is to provide a game of dice which increases the 25 opportunity for judgment during the game, and to provide a game in which there is no specified limit to the score.

The invention will be hereinafter more particularly described with reference to the 30 accompanying drawings, which form a part of this specification, and will then be pointed out in the claims at the end of the description.

In the drawings, Figure 1 represents the 35 six sides and the characters or markings of what I call the ruling or combination die. Fig. 2 represents the six sides of one of the regular dice or objects. Fig. 3 illustrates the progress of the game showing a succession 40 of throws of one of the players; and Fig. 4 is a view similar to Fig. 3, showing the result of several throws by a second player.

While I shall describe a particular form of 45 dice and characters thereon and one way in which the game may be played, the nature of the dice or other objects employed may be varied and the characters on the objects, and also the method of playing the game may be changed without altering the nature 50 of the invention.

The game as ordinarily played has a combination die or object 10 marked on three of its faces with the word "High" with one to 55 three spots which may be termed "High 1", "High 2" etc., and on the remaining three faces with the word "Low" also with one to

three spots or characters as shown in Fig. 1. The remaining dice 11 may be four in number and each die has a blank face, or may have a zero mark, and the other faces are 60 provided with spots or characters from one to five, the blank space taking the place of the usual six spot and these dice or objects may be called "blank fives."

The result sought in playing "High" is to 65 obtain twenty points, and in playing "Low" to obtain all blanks and therefore count nothing. Whether it is to be "High" or "Low" is determined by the first throw, that being the only throw in which the combination die 10 70 is used, the remaining throws or tosses being with the other dice, as shown clearly by Figs. 3 and 4 in which A indicates the one playing "High" and the other "Low" indicated by B. It will be seen that the combination 75 die 10 of player A has two spots and the die 10 of player B has one spot, these dice therefore indicating that player A is to seek twenty points, and player B four blanks or nothing. The number of spots on the device 80 10 govern the play to the extent that the player may have what I call a "break" for each spot on the combination die and there may be either one, two or three "breaks" according to which face of the die is uppermost on the first throw. By a "break" is intended 85 an interruption in the progress of the game, as it is a part of the game to advance progressively at each throw over that of the previous throw. That is in playing "High" 90 if the aggregate of the first throw as in Fig. 3 is 12, independent of the combination die 10, each succeeding throw must count more than the one previous, otherwise there will be a "break"; while in playing "Low" as in Fig. 95 4, each succeeding throw after the first must aggregate less than the previous one otherwise there will be a "break", the purpose in the latter as before stated being to secure four blank faces, and in the former four faces 100 with five spots making twenty points.

The invention will be more easily understood by reference to Figs. 3 and 4, and each of these figures will be described separately as they illustrate a possible game between 105 two players. The first throw and in which the die 10 is used indicates that the player is entitled to two "breaks" and must seek to obtain twenty points by each die indicating five points. The first throw aggregates 110 twelve, and each throw must progress by making a higher count. In the second throw

dice 12, 13 and 14 are used again, as the object is to turn up a face having five spots, and the result of this throw makes seventeen, which is greater than the previous throw, so that the game continues. On the third throw dice 15 and 16 are used again, and as the total is only twelve and less than the former throw there is a "break". The player has one more "break" besides the final one which terminates the game, so he makes a fourth throw using dice 17 and 18, and as this results in twelve also and being a tie, and therefore not counting, the game continues using dice 19 and 20. On this throw the total is eighteen, and die 21 is used again in making the sixth throw, and as this totals twenty the player has made one "run". The player starts over again using all four dice, and on the seventh throw, or first of the second "run", makes a total of twelve, and as the next throw is less than the preceding one a second "break" occurs. The next throw totals fifteen, but as the tenth throw only totals thirteen, being less than the preceding one, a final "break" occurs. The die 10 indicates that the player is entitled to two "breaks" so the third or final "break" completes the game so far as this player is concerned.

In counting the score made by A the total of the final "break" is deducted from twenty or the number sought, which leaves seven. To the seven is added the number on the combination die 10 making nine, and putting the two of the combination as an affix makes ninety-two the score of A. The run in the sixth throw makes the exact score or one "run" ninety-two.

The number on the combination is in the nature of a fine and is always added to the score, for the player who makes the greatest numbers of "runs" and the lowest score always wins.

Player B proceeds exactly the same as A, but in this case the die 10 indicates "Low" and the player is only entitled to one "break". Here the total is nine and the score must decrease progressively and the player seeks to secure four blanks. As already explained the player in each throw uses the dice not blanks of the preceding throw, and in the second throw can use die 22 or not as preferred. As the result of the second throw is greater than the first, a "break" occurs, and one more "break" is the final one. The third and fourth throws tie and therefore do not count, and as the fifth and sixth throw are each less than the one preceding, the game continues to the seventh, and as the total is in excess of the preceding throw, a final break occurs.

The score for B is two with the combination added making three, and with the affix of the combination, which is one, added the score is thirty-one. Had B scored one "run"

the score then would have been one "run" thirty-one, which would beat the score of A of one "run" ninety-two. That is the greatest number of "runs" with the lowest number wins the game.

A player does not have to go to the end of the game. While the player may take advantage of all of the "breaks" allowed by the combination die 10, he need not do so, as he might stop after the first "break" or even after the first throw should the count prove satisfactory. In either of these cases the number indicated on the combination die must be added in the way of a penalty.

While the possibility of one player tying another is remote, still no player can stop and score and make such score tie the score of a previous player. The only chance there is to tie the score of a previous player is after the final "break", and this is not likely to happen. In other words a player must not tie another's score, if the combination die permits him to continue, but if a tie should happen after the final "break" it will have to stand. If the score of a third player (there may be any number of players) does not beat the score of those who have made the same score, then the latter have one more throw each with all five dice, and the score is figured as already explained. After one player wins, then the remaining ones start all over again, and after a second game is won, then those remaining continue the game.

From the foregoing it will be seen that a simple and interesting game of dice is provided; that the possibility of a tie occurring is reduced to a minimum; that a game capable of many variations is provided; and that the opportunity for using judgment is greater and therefore the game made more attractive, than is the case with the usual game of dice.

Having thus described my invention, I claim as new and desire to secure by Letters Patent:—

1. A game apparatus comprising a plurality of objects each having a plurality of sides differently marked and provided with a blank side, and a ruling combination object also having a plurality of sides and differently marked from the other objects and serving to govern the progress of the game.

2. A game apparatus comprising a plurality of dice each having sides progressively marked up to five and having a single blank side, and a combination die also having six sides and differently marked from the other dice and serving to govern the progress of the game.

3. A game apparatus comprising a plurality of objects each having six sides five of which are differently marked, and a combination die also having six sides and differently marked from the other objects and three sides differently marked from the other

three sides and serving to govern the progress of the game.

4. A game apparatus comprising four dice each having six sides, certain of the sides being progressively marked up to five, and a combination die also having six sides, three of which sides are marked with the word "High" and characters from one to three, and the other sides with the word "Low" also progressively marked with characters from one to three.

5. A game apparatus comprising four objects each having a plurality of sides differently marked, and a combination object having a plurality of sides, some of which sides are marked with the word "High" and other characters, and the other sides with the word "Low" also with other characters.

6. A game apparatus comprising a plurality of dice each having sides progressively marked up to five and a sixth side, and a combination die having six sides, three of said sides being marked with the word "High" and characters from one to three, and the other three sides with the word "Low" also progressively marked with characters from one to three.

7. A game apparatus comprising a plural-

ity of objects each having a plurality of sides differently and progressively marked, and a combination object having a plurality of sides marked with certain characters and other sides marked with characters different from the characters on the first mentioned objects.

8. A game apparatus comprising a plurality of dice each having sides differently and progressively marked up to five and a sixth side, and a combination die having six sides marked with characters different from the characters on the first mentioned dice.

9. In a game apparatus, a plurality of objects each having five sides differently and progressively marked, and each having a single blank side.

10. In a game apparatus, a plurality of dice each having six sides certain of said sides being progressively marked up to five and each having a single blank side.

This specification signed and witnessed this 2d day of December A. D. 1907.
